DES. 2275

Composed & corrected. Samuel Killell of San Francisco, Cal.

Dec. 11-1875, S. M. Letters Patent No. 2275 Dated March 6, 1866.

Design for Architectural Center Flowers.

The schedule referred to in these Letters Patent and making part of the same.

Yours whom it may concern:

Be it known that I, Samuel Killell, of the City and County of San Francisco, State of California, have originated and designed a new pattern for Center Flowers, for buildings, etc., of which the following is a full, clear and exact description reference being had to the accompanying drawings making part of this specification, in which there is a photograph representing a "center flower" of my designing.

My said center flower is composed of plaster of paris, so called, modeled and cast in the way, well known to workers in stone, and consists of four arms placed at right angles, surrounded by scroll work. The center is of plaster to cast separate and placed upon the arms. The corner four in number are cast separate, and consist of lattice or basket work, surrounded by scroll work, placed upon the arms in the usual way.

Hearing thus described my design for "center flowers", what I claim and desire to secure by Letters Patent is the design or pattern for center flowers herein set forth.

In witness whereof I have signed at my hands and seal this 4th day of January in the year 1866.

Witnessed

for Mosheimer.

Sam'l. Killell. 333 P.H. S.
